ROTARY PUMP, COMPRESSOR, MOTOR,
AND THE LIKE

William Morgan, Clifton, Bristol, England

Application August 30, 1933, Serial No. 637,525
In Great Britain September 2, 1932

4 Claims. (Cl. 103—141)

This invention has reference to rotary pumps, compressors, motors and the like of the feathering-vane type, wherein the stator casing is provided internally, and intermediate its intake and delivery ports, with one or more stationary and circumferentially-arranged fluid-abutments, each of which engages a circumferential working chamber in the vane-carrying rotor and the vane (or each vane) of the machine is so mechanically-controlled that, during its rotation with the rotor, it is also constrained periodically to change the aspect of its working face and to make such an annular "feathering" movement within the working chamber as will enable the said vane to pass from the high-pressure side to the low-pressure side of the fixed fluid abutment.

The specification of British Letters Patent No. 341,013 describes machines of this type, in which the feathering mechanism imparts to each vane, a continuous rotational movement of constant or uniform velocity; the construction of the various parts being such that whilst each vane is positioned across the working chamber during the greater part of the cycle, the feathering mechanism operates, as the vane approaches the abutment, so to position the said vane that it may pass the said abutment.

In such machines, however, the rotating vane has to be permitted a substantial angular movement in passing the stationary abutment, and to provide for this, the clearances which have to be arranged for between the vane blades and the sides of the abutment must be of such magnitude that substantial fluid transfer may occur between the high pressure and the low pressure sides of the abutment, with consequent loss (especially where gases are being dealt with) in the volumetric efficiency of the machine. Furthermore, where a pair of vanes are fixed to the opposite ends of a common spindle which is continuously rotated by the feathering mechanism, the vanes must be arranged in planes at right angles to one another in order that they may be successively carried past the stator abutment by the revolving rotor. This arbitrary consideration imposes a limitation upon that period of the cycle during which each vane is effective as a fluid-impelling or fluid-impelled member; and it may also, in some constructions, impose limitations on the cross-sectional area or capacity of the working chamber that can be embodied in a machine of any given dimension.

One object of the present invention is to enable the reduction of the working clearances between the rotor vanes and the stator abutment, and also

to enable the cross-sectional area of the working chamber to be substantially increased relatively to the cross-sectional area of the vane-passage or passages in or at the vicinity of the stator abutment, with consequent avoidance of transfer losses and improved volumetric efficiency as compared with machines of the continuously-rotating vane type. 5

A further object is to provide, in multiple-vane machines, oscillatory-control mechanisms 10 which will enable such relative setting of the feathering vanes that each vane may be made operative through an angle greater than 90°, with consequent increase in the cross-sectional area or capacity of the working chamber irrespective 15 of the cross-sectional area of the vane passage or passages in or at the abutment.

According to the said invention, either or both of the above-mentioned objects may be realized by providing, in combination with vanes adapted 20 to have a feathering action, control mechanism which is adapted to impart a varying or harmonic oscillatory movement to the rotor-revolved vanes, and which is preferably so timed in its operations that, as regards each vane so controlled, a change in the direction of oscillation, with consequent minimum angular movement, 25 may be made to synchronize, or approximately synchronize, with the travel of that vane through or past the stator abutment. 30

From this it results that, since only small angular vane movements have to be provided for between the surfaces, the clearances between vane blades and abutment faces may be reduced to small magnitudes, and since with oscillatory 35 feathering action, right-angled settings of the vanes at the opposite ends of a common spindle are no longer arbitrary, any relative setting within substantial limits (greater or less than 90°) may be adapted to suit the particular requirements of a given pump, motor, or other machine. 40

Having regard to the general characteristics of the rotary pumps, motors, and the like to which the present invention is applicable, it is desirable that whatever form of vane-control mechanism 45 is employed, it must be capable of being driven by the rotor and be adapted to convert the rotary drive into oscillatory motion at the vane spindle or spindles. Given these capacities, various mechanisms may be adopted for the purposes of the 50 present invention, but the constructions herein-after described with reference to the accompanying drawings are set out as examples of compact and efficient mechanisms which, by suitable modification in detail, may be adapted to oscillate 55

a vane spindle through an angle of any desired effective amplitude, according to requirements.

In the accompanying drawings, wherein for the purpose of illustration, I have shown several 5 preferred embodiments of my invention, and wherein like reference characters have been employed to designate like parts throughout the several views,

Fig. 1 is a fragmentary, sectional view through 10 a portion of the rotor, showing one form of vane-oscillating mechanism,

Fig. 2 is a fragmentary, vertical sectional view through a portion of the rotor and stator;

Fig. 2A is a fragmentary sectional view of a 15 portion of a rotor having two circumferential working chambers, this view showing a three-blade oscillatory vane in an impelling or working position,

Fig. 2B is a view similar to Fig. 2A but showing 20 the oscillatory vane having its blades alined with the rotor chambers to permit the rotor to pass the spaced abutments carried by the stator.

Fig. 2C is a fragmentary, sectional view on the 25 line C—D of Fig. 2D, showing an oscillatory vane of double blade construction, this view showing the vane in a position to pass the abutment carried by the stator,

Fig. 2D is a sectional view on the line A—B of 30 Fig. 2E,

Fig. 2E is a fragmentary, vertical sectional view, showing one of the recesses formed in the 35 inner face of the stator chamber adjacent the abutment, to accommodate the vanes as they are moved to abutment-passing position,

Fig. 3 is a fragmentary view, partly in section, 40 of a modified form of the vane-oscillating mechanism,

Figs. 4 and 5 are fragmentary views, partly in 45 section, of a further modified form of the vane-oscillating mechanism,

Figs. 6 and 7 are, respectively, fragmentary vertical and horizontal sectional views through a 50 portion of a rotor and stator showing a further modified form of the vane-oscillating mechanism, and

Figs. 8 and 9 are, respectively, transverse, fragmentary vertical and horizontal sectional views through a portion of a rotor and stator, showing a still further modified form of the vane-oscillating 55 mechanism.

Each mechanism essentially comprises an anchored member which constitutes or carries a stationary fulcrum that provides for the conversion or transmission of the rotary motion of the revolving rotor-and-vane assembly into oscillatory motion in transmission to the vane spindle, since any point or area which is offset in relation to the rotor axis may be so mechanically coupled, articulated, or linked to the vane-spindle as to produce, 60 in the latter, the oscillation derived from the revolving assembly.

In the application illustrated diagrammatically in Figure 1 of the drawings, the rotor *a* embodies a slide-bar *b* set perpendicular to the axis of the vane-spindle *c* and radial to the rotor axis; the same being adapted to reciprocate in guides *a'* in the rotor casing. The shaft of the fixed fulcrum member *d* is extended through a hollow journal of the rotor and carries, on its inner face, a crank-pin *d'* which is off-set from the centre of the said fixed shaft *d*. This crank pin is coupled to the slide-bar by a connecting link *d''*, and the bar is in turn coupled to the vane-spindle *c* by another connecting link and crank *d'''*.

The vanes *c'* *c''* may be fixed to the opposite

ends of the vane spindle, at right angles (or at a greater or less angle) relative to one another as shown in Figure 2, and the whole vane and rotor assembly is arranged to revolve within the stator casing *e* which internally embodies, in a position intermediate the fluid intake and delivery ports *e'* *e''* stationary fluid abutments *f*, each of which (when two abutments are used) engages a circumferential working chamber of the rotor. The spindle oscillating mechanism is so timed in its operations that, as each vane of the revolving assembly approaches the stationary abutment *f*, the said vane is "feathered" from its working position across the chamber and brought towards such alignment with the said chamber 10 as will enable the abutment to be passed; the actual passing being synchronized, by the control-gear timing, to occur during the slowing down in the angular velocity of the vane spindle which results from the reversal of the direction of 15 oscillation of the spindle.

Instead of connecting the slide bar to the vane spindle by a connecting link as shown in Figure 1, the connection may be made by a pin fixed to the vane spindle and slidably engaging a swiveling attachment on the slide-bar.

Another construction of vane oscillating gear is shown diagrammatically in Figure 3, where a pin *d'* is carried by the fixed shaft *d* in off-set relation to the centre of the latter. This crank pin is free to rotate in its bearing and is also restrained against endlong movement. The inner end *d''* thereof is adapted to slide upon a wrist-pin *d'''*, which is held parallel with the vane spindle *c*, and engages jaws or forks in rocker arms *c'* which are fixed to the said spindle *c*. With this construction, as the rotor-and-vane assembly is revolved, the wrist-pin *d'''* is, by virtue of its sliding connection with the off-set swivelling pin *d'*, constrained to move harmonically with reference 40 to the axis of the vane spindle and to transmit a corresponding oscillation to the vane spindle. In a modification of this construction, the wrist-pin *d'''* may be pivoted to the rocker-arms *c'* and the off-set pin *d'* may be so mounted in the 45 stationary member *d* that it is free to move endwise in its bearing as well as to swivel therein.

A further construction of control gear is illustrated in Figures 4 and 5. Here the stationary or anchored member of the system consists 50 of a Z-shaft whose ends *d''* are carried in journals aligned with the rotor axes, and whose pin *d'* is supported between the off-set cranks *d''* obliquely across the interior of the rotor in such a plane that the axis of the said pin *d'* intersects the axis of the vane spindle *c*. The point of this intersection is also coincident with the axis of rotation of the rotor. The oblique pin *d'* may be arranged at an angle of 45° to the shaft ends *d''*, or at any other desired angle, according 55 to the amplitude of oscillation to be imparted to the vane spindle.

The vane spindle *c* is cranked at *c'* as shown in Figure 5 to give the necessary oscillating clearance between the said spindle and the oblique pin *d'*, and the said pin *d'* and the spindle crank *c'* are coupled by a Y-shaped link or stirrup *d''*, the head-arms *d'''* of which embrace, and are free to turn upon, the pin *d'*, whilst the stem *d''* has a free swivelling or pivotal and sliding connection with the crank *c'* of the vane spindle.

With this construction, when the rotor-and-vane assembly is revolving, the stirrup *d''* is constrained, by its connection with the vane-spindle, to turn upon the stationary pin *d'*, and by vir-

ture of the oblique disposition of the latter, the stem d^{11} of the stirrup d^9 is rocked or oscillated in the plane containing the point of intersection of the various axes and imparts a corresponding oscillation to the vane-spindle crank.

A still further construction of vane-control gear is shown in Figures 6 and 7 where the stationary or anchored shaft-member d carries a crank d^{11} which is located within the rotor chamber intermediate the vane spindle c and the outer wall of the rotor. This crank supports, in off-set relation to the centre of the shaft d , a stud or short spindle d^{12} which is free to revolve in the crank and is disposed obliquely to the anchored shaft at an angle of 45° or otherwise, according to the amplitude of oscillation to be imparted to the vane spindle. In the illustrated construction, the spindle d^{12} is set at an angle of 45° to the shaft d and the parts are so arranged that the axes of the said spindle and shaft would, if produced, intersect one another at a point in the vane-spindle about mid-way between the vane-carrying ends.

At this mid-point, the vane-spindle is furnished with a wrist-pin c^{12} which is extended from the opposite sides of the said spindle to provide a pair of trunnions to which are respectively journalled the arms c^{13} of a U-shaped stirrup link c^{14} whose cross-pin c^{15} is so journalled in the off-set anchored spindle d^{12} that the said stirrup link may rock or oscillate in and relatively to the said spindle.

The wrist-pin on the vane spindle of the rotor-and-vane assembly is thus so coupled by the rocking stirrup link to the oblique and off-set anchored spindle that, when the said assembly is revolved relatively to the anchored member, the vane spindle is constrained to oscillate and to change the direction of its angular movement twice during each cycle of the rotor. These oscillations are preferably so timed or controlled that (in the case of a double-vane machine such as illustrated in these Figures 6 and 7) each change in the direction of the oscillation of the spindle synchronizes (actually or approximately) with the passing of the stator abutment f by one of the vanes c^1 , c^2 .

According to a further application of the invention whereby the above-discussed advantages may also be realized, the controlled oscillation of the vane-spindle may be provided for by a swash-plate type of mechanism as in the construction shown in Figures 8 and 9 where the anchored shaft of the system embodies an oblique-faced off-set member which, in effect, is a mechanical equivalent to the anchored oblique crank-pin of the construction shown in Figures 4 and 5 or the oblique anchored spindle of the construction shown in Figures 6 and 7.

In the construction shown in the said Figures 8 and 9, the vane spindle c embodies, mid-way between its vane-carrying ends, a gimbal-ring c^{14} in which a swash-plate c^{15} is so pivoted that it may swing about an axis at right angles to the axis of the vane-spindle, which latter axis passes through the point of intersection of the axes of the rotor and the vane spindle. The stationary or anchored shaft d is furnished with a fulcrum member d^{15} fashioned to present an inclined plane surface with which the swash-plate c^{15} engages. The parts c^{15} , d^{15} , are so positioned that the common plane of contact between the co-engaging surfaces passes through, or approximates to, the intersections of the axes of the rotor and the vane spindle, and from this arrangement it results

that, as the rotor-and-vane assembly is revolved, the rocking swash plate is maintained in contact with, and is oscillated by its movement with respect to, the oblique face of the anchored member; this oscillation being so transmitted to the vane spindle that the latter changes its direction of movement twice during each revolution of the rotor; each change being timed—in the case of a two-vane machine as shown—to synchronize with the travel of one of the vanes c^1 , c^2 , past the stator abutment f .

In all the vane-oscillating mechanisms described, their operations are so timed that as a vane is approaching the stator abutment, the angular velocity of its angular displacement is slowed down in attaining the impending change of direction and consequently the vane will experience the minimum angular displacement in passing the abutment. This enables the faces of the vanes and abutments to be profiled or contoured with minimum clearances without materially affecting the efficiency of the vanes as sealing valves whilst travelling past or through an abutment. Further, the vane passage or passages in or at the abutment may be made of a cross-sectional area substantially less in proportion to the cross-sectional area of the working chamber than is possible in machines where the vanes are given a continuous rotary movement of uniform velocity.

Where the vanes at the opposite ends of the spindle are set at right angles to one another and each oscillates through an angle of 90° , the inclined fulcrum surface on the anchored member is pitched at an angle of 45° to the axis of the said spindle, but where a greater or less angle of oscillation is required, the angle of the said fulcrum surface is correspondingly varied. In fact, in the whole of the constructions of vane-control mechanisms which involve the use of an inclined fulcrum-pin or fulcrum-surface, the amplitude of the angle of vane oscillation is a factor which can be varied within wide limits by the selection and use of a suitably inclined fulcrum, whereas in those constructions in which oscillation is derived from a crank pin or fulcrum off-set from the axis of a stationary or anchored crank-shaft or like member, any desired amplitude of oscillation (within wide limits) may be provided by suitably predetermining the off-setting of the fulcrum and the relative dimensions of the linkages. It is, of course, understood that where vanes are required to oscillate over an angle greater or less than 90° , then, instead of setting the vanes at the opposite ends of the spindle at right angles, they are set to each other at an angle equal to that of the oscillation amplitude to be imparted to the spindle by the vane-control mechanism.

The sense of this angle may be determined by ordinary mathematical principles, or it may be ascertained or arrived at during the assembly of the machine by procedure of fixing only one vane to its spindle (leaving the other temporarily free or loose), mounting the spindle in the rotor and adjusting the same to the position wherein the fixed vane is set to pass the stator abutment, then turning the rotor and adjusting the loose vane also to pass the abutment; finally keying the last-mentioned vane in its adjusted position to the spindle.

Oscillatory-vane control mechanisms such as herein described may advantageously be applied to pumps, motors and the like in which the periphery of the rotor is formed, as shown in Figures 2, 2A, and 2B, with two circumferential work-

ing chambers x , x^1 , separated intermediate the vane-housings x^3 by an interrupted partitioning rim or web x^2 . Each chamber is engaged by a fixed fluid-abutment f and vanes c are constructed 5 with three blades as illustrated in Figures 2A and 2B, where Figure 2A shows one of the vanes in an impelling or working position, with the blades disposed across the peripheral fluid-chambers, whereas Figure 2B shows the vane with the blades 10 aligned to the said chambers and passing the fixed abutments.

Alternatively, the oscillatory vane-controls may be applied to machines such as described in British specification No. 341,013, in which 15 single-blade vanes are arranged to operate in circumferentially-partitioned fluid-chambers and to pass between double-bladed stator abutments as and when the vane blade is brought into 20 alignment with the partitioning rims between the chambers.

As a further alternative, the oscillatory controls may be applied to machines in which double-bladed vanes are used in a rotor which is formed with a single circumferential fluid chamber x^4 as shown in Figures 2C, 2D, and 2E. In such a case, the blades of the vane pass on opposite sides of the stator abutment f in their travel past the latter as illustrated in Figure 2C, where the vane is shown at the end of its 25 oscillation in one direction and, therefore, momentarily at rest in the oscillatory sense, and about to move in the opposite direction as shown by the arrow.

But whether the three-bladed or the two-bladed construction of vane is adopted, recesses are formed in the outer walls of the fluid chamber or chambers to accommodate or contain the side-blades when the vanes are "feathered" to the abutment-passing position.

Having described my invention, what I claim and desire to secure by Letters Patent is:—

1. In a rotary pump and the like, a stator including a rotor chamber provided with spaced inlet and outlet ports and with a fixed abutment positioned intermediate said inlet and outlet ports, an anchored member within said rotor chamber, a rotor within said rotor chamber provided with a peripheral channel receiving the fixed abutment and carrying a feathering vane 45 mounted on a vane spindle, said rotor and vane assembly revolving about said anchored member with the vane normally intersecting said rotor channel, means operable by movement of the rotor for imparting oscillatory movement to the vane spindle to permit said vane to pass said abutment during rotation of said rotor, said means comprising a mechanical coupling extending between said vane spindle and a stationary point on said anchored member, said stationary point being offset with respect to the axis of revolution of the said rotor and vane assembly.

2. In a rotary pump and the like, a stator including a rotor chamber provided with spaced inlet and outlet ports and with a fixed abutment positioned intermediate said inlet and outlet ports, an anchored member within said rotor chamber, a rotor within said rotor chamber provided with a peripheral channel receiving the

fixed abutment and carrying a feathering vane mounted on a vane spindle journaled in the rotor, said rotor and vane assembly revolving about said anchored member with the vane normally intersecting said rotor channel, means operable by movement of the rotor for imparting oscillatory movement to the vane spindle to permit said vane to pass said abutment during rotation of said rotor, said means comprising a mechanical coupling extending between said vane spindle and a stationary point on said anchored member, said stationary point being offset with respect to the axis of revolution of the said rotor and vane assembly. 5

3. In a rotary pump and the like, a stator including a rotor chamber provided with spaced inlet and outlet ports and with a fixed abutment positioned intermediate said inlet and outlet ports, an anchored member within said rotor chamber, a rotor within said rotor chamber provided with a peripheral channel receiving the fixed abutment and carrying a feathering vane 20 mounted on a vane spindle, said rotor and vane assembly revolving about said anchored member with the vane normally intersecting said rotor channel, means operable by movement of the rotor for imparting oscillatory movement to the vane spindle to permit said vane to pass said abutment during rotation of said rotor, said means comprising a mechanical coupling extending between said vane spindle and a stationary point on said anchored member, said stationary point being offset with respect to the axis 25 of revolution of the said rotor and vane assembly, the oscillating movement of the vane spindle being timed with reference to the travel of the vane past the stator abutment, whereby the change of direction of vane oscillation approximately synchronizes with the travel of the vane past the abutment. 30

4. In a rotary pump and the like, a stator including a rotor chamber provided with spaced inlet and outlet ports and with a fixed abutment positioned intermediate said inlet and outlet ports, an anchored member within said rotor chamber, a rotor within said rotor chamber provided with a peripheral channel receiving the fixed abutment and carrying a feathering vane 45 mounted on a vane spindle journaled in the rotor, said rotor and vane assembly revolving about said anchored member with the vane normally intersecting said rotor channel, means operable by movement of the rotor for imparting oscillatory movement to the vane spindle to permit said vane to pass said abutment during rotation of said rotor, said means comprising a mechanical coupling extending between said vane spindle and a stationary point on said anchored member, said stationary point being offset with respect to the axis of revolution of the said rotor and vane assembly, the axis of oscillation of the vane spindle intersecting the axis of revolution 50 of the rotor and vane assembly, said mechanical coupling being disposed obliquely with respect to the axes of the vane spindle and rotor. 55
